UNITED STATES PATENT OFFICE.

RUDOLF EICKEMEYER, OF YONKERS, NEW YORK.

ELECTRIC LOCOMOTIVE.

SPECIFICATION forming part of Letters Patent No. 443,671, dated December 30, 1890.

Application filed January 28, 1889. Serial No. 297,775. (No model.)

To all whom it may concern:

Be it known that I, RUDOLF EICKEMEYER, of Yonkers, in the county of Westchester and State of New York, have invented certain new and useful Improvements in Electric Locomotives; and I do hereby declare that the following specification, taken in connection with the drawings furnished and forming a part of the same, is a clear, true, and complete description of the several features of my invention.

It is well known that persons riding on electric locomotives as heretofore organized are exposed to the liability of more or less annoyance and expense resulting from the derangement of their watches caused by external magnetism unduly projected from the field-magnets of the motor. It is not new to guard against said objectionable projection of magnetism by covering adjacent portions of the car or locomotive with sheets of iron, or to employ a separate guard or casing between an ordinary electric motor and the passenger portion of the car or locomotive; but so far as my knowledge extends I am the first to render such a guard or shield unnecessary, because my electric locomotive embodies the novel combination, with the car-body and its driving shaft or axle and suitable gearing, of an electric motor containing an armature having a core of magnetic metal, field exciting-coils which surround the armature, and an iron shell or casing, which constitutes a part of the magnetic system of the motor and incloses said armature and coils, and affords a highly effective internal magnetic field without any possibility of the projection of magnetism into the car or cab, because, although the motor may be directly secured to the sill-framing of the car, and therefore closely adjacent to the interior of the car, there is between said framing and the interior magnetic field of the motor a portion of the motor shell or casing which is a part of the magnetic system and traversed by a portion of the magnetic circuit which is completed within the motor. By thus organizing the motor great strength and high efficiency can be obtained without undue weight, and the shell or casing can be firmly and rigidly attached to the under side of the sill-framing of a car-body, thus obviating the use of a separate frame structure for carrying the motor

in a suspended condition below the car and relieving the motor from all vibrations and shocks other than those experienced by the car-body supported on its springs, thus securing maximum durability in the bearings of the motor, and also at its immediate connections with the driving-gearing.

Although the motors now used by me in electric locomotion embody valuable features heretofore patented by me, I have succeeded, as the result of an extended series of costly practical experiments, in now successfully adapting them to street-car service, with special reference to the development of greater power, with less weight in the motor, than any prior street-car motor known to me.

Now, inasmuch as an avoidance of unnecessary weight in an electrically-operated street-car is far-reaching in its economic results, I deem it a prime feature in my present invention to have for the first time devised and applied to practical service an electric-locomotive organization which embodies with the driving-wheels and suitable driving connections an electric motor having an armature which has an iron core and is surrounded and directly polarized by field exciting-coils, and which has also a magnetic shell or casing which affords a magnetic circuit for the lines of force, and is also mounted on or carried by, and preferably pendent from, a spring-mounted car body or truck. This portion of my improvement secures ample power and reliable operation, with the avoidance of many hundreds of pounds in weight of iron and copper, resulting in substantial economy in construction and maintenance; also in wear and tear of wheels, rails, and throughout the working parts of the locomotive, and also in an economic expenditure of electrical energy.

My improvements also relate in part to means for the transmission of power from a motor-shaft to the driving-axle of a car; and another object of my invention is to relieve the motor from such objectionable shocks and jars as are inevitably communicated thereto from the driving-axle through such gearing as has been generally heretofore employed, and also to enable the motor to be rigidly attached to the car-framing and to vibrate vertically with a spring-supported car-body without causing shocks or jars to any of its bear-

ings or to any portion of the gearing or other coupling mechanism by which the motor and driving-shaft are connected, and I also seek to measureably relieve the gearing from such undue strains as are liable to result from the momentum of the armature following the sudden checking of its speed. For accomplishing these ends I have for the first time, as I believe, operatively connected the armature-shaft of the motor with the axle of the car by means of pitmen connecting the motor-shaft with a counter-shaft occupying the same vertical plane as the axle and carried thereon, but coupled by links or frame-pieces hinged to the motor on bearings preferably concentric with the motor-shaft, and I have geared the counter-shaft and axle together, so that the meshing-point of the gears is located in the vertical plane occupied by said shaft and axle, and also so that their relative positions will be maintained during the ordinary rise and fall of the car-wheels at the ends of the axle, and, still further, so that the motor-shaft and counter-shaft will maintain such uniform relations that the pitmen may operate smoothly, effectively, and durably, and, still further, the motor is so coupled to said counter-shaft and so located in the same horizontal plane that the reciprocatory movements of the pitman in transmitting power from the motor cannot cause any vertical vibration of the spring-supported car-body.

Another object of my invention is to provide against injury to the motor or to any of the mechanism between it and the driving-shaft in the event of their being subjected to driving strains greater than their maximum strength or safety limit; and to that end I have frictionally connected the counter-shaft to its gear or pinion, so that whenever undue and dangerous strains are in any manner encountered the counter-shaft may revolve independently of the gearing, and I have also provided for a yielding contact at the frictional couplings, and also for varying their adhesive contact, so as to enable such an adjustment thereof as will secure the performance of only such duty as may from time to time be deemed absolutely safe and proper. I have also mounted upon the counter-shaft and axle a housing which completely incloses the pinion and gear and thoroughly protects them against abrasive matter, renders the gearing practically noiseless, and which also serves as a reservoir for liquid lubricating matter, with which the gearing may be abundantly and continuously charged while in motion.

To more particularly describe my invention, I will refer to the accompanying drawings, and after a detailed description thereof the features deemed novel will be specified in the several clauses of claim hereunto annexed.

Figure 1, in side view, illustrates the lower portion of a car-body with my improvements applied thereto. Fig. 2 is a top view of the mechanism with the car-body removed, but

with the car-sill framing indicated in dotted lines. Fig. 3 illustrates the driving-axle longitudinally, and also the counter-shaft, with the mechanism which connects them shown in section. Fig. 4 is a side view of one of the counter-shaft bearings and the means by which it is connected, respectively, with the driving-axle and the motor. Fig. 5 illustrates the gearing in side view, and the axle, counter-shaft, and a gearing-casing in section.

The sill-framing A of the car-body or locomotive may be variously constructed and arranged, and such ordinary cars now in use as have proper strength of framing may have my improvements readily applied thereto. As here shown, the locomotive has one axle and a pair of wheels, as in ordinary street-cars, and the driving shaft or axle B has wheels smaller than the other pair, as is necessary when my improvements are specially adapted for use on ordinary cars; but with a car or cab specially constructed for receiving said improvements the wheels on the driven axle may be of any desired diameter, and so, also, if desired, may the wheels on the two axles be of uniform diameter and coupled together, as in ordinary steam-locomotives. The cushioning of the car-body by means of springs is, as usual, on both axles, although the box jaws or pedestals for the driven axle are longer than those of the axle of the car. The electric motor C is specially organized for this duty, and it contains an armature having an iron core, and field-coils which surround said armature longitudinally, and these are all inclosed by a shell or casing of iron, which affords appropriate pole-faces without any appreciable external magnetism. The casing or shell a is clearly shown and said armature and field-coils are within said casing, as is well indicated in dotted lines in Fig. 2. If need be, a more complete knowledge of such motors may be obtained by reference to my Letters Patent No. 358,340, dated February 22, 1887. The motor is applied directly to the sill-framing of the car by means of angle-iron brackets b and suitable bolts, thus avoiding all intermediate frame-work and securing a firm, rigid, and absolutely reliable connection with the car-body. The top of the iron shell or casing a lies parallel with the floor of the car, and the magnetic circuit is so restricted to said casing as to absolutely preclude the extension of the magnetic field upward to the interior of the car, and the watches of passengers can never be exposed to injury from that cause, inasmuch as I have for the first time in an electric locomotive interposed between persons riding thereon and the magnetic field developed by the field-coils what is in substance and effect a reliable magnetic shield or guard, beyond which magnetism cannot be projected. A motor thus organized need involve but little weight of iron beyond what is actually needed to afford the required magnetism, and being thus directly attached to the car-body, it is obvious that there need

be little or no surplusage of burden in the motor or in its supporting connections. It will also be obvious that substantial economy accrues from the simplicity in construction 5 of the motor as well as in its application to a car, and that wear at the bearings of the motor-shaft is reduced to a minimum because of the non-liability of shocks or jars other than those experienced by the car-body.

10 The driving-axle B may be operatively connected in various ways with an electric motor constructed and mounted as described, without departure from certain portions of my invention, but I have devised connecting mechanism involving novel features.

Above the driving-axle B, and parallel therewith between its wheels, I have mounted a counter-shaft D, having its bearings in two arms c c', supported upon and hinged to loose 20 sleeves d d' on the axle B, and also hinged at their opposite ends to the motor, and preferably concentric at the hinging points with the armature-shaft e of the motor. The hinge-bearings of these arms d d' at the motor are 25 straight or cylindrical, so that said arms can have no torsional action, but the bearings of the counter-shaft in said arms are of the ball-and-socket variety, as is clearly indicated in Fig. 3.

30 As thus far described, it will be seen that the counter-shaft is supported upon the axle B in the same vertical plane, and that when either end of said axle rises or falls, as when the wheels override rail-frogs or slight obstructions, the counter-shaft will maintain its 35 parallelism with the axle without any binding effect at its bearings, and also that the arms d d' cause the counter-shaft to always maintain a certain uniform position with relation to the armature-shaft e of the motor. At the ends of the armature-shaft there are 40 crank-disks f f', which are connected by means of pitmen g g' to crank-disks h h' on the two ends of the counter-shaft. The wrist-pins on 45 the disks f f' are straight or cylindrical, and the wrist-pins on the disks h h' are ball-shaped, so that requisite flexibility will be afforded between the pitmen and counter-shaft during any rocking movement of the 50 car-body or during the tilting movement of the axle and counter-shaft. The crank-disks are set quartering in a well-known manner for securing uniform transmission of power from the armature-shaft to the counter-shaft, 55 and the force of the armature-shaft is transmitted to the counter-shaft in lines which are always parallel with the planes occupied by the corresponding ends of the two shafts. It will be seen that inasmuch as these two shafts 60 are normally in one horizontal plane, and as the force of the motor is transmitted in the same plane the car-body cannot be lifted or depressed on its springs, or, in other words, vertically vibrated by the operation of the 65 motor, nor can the rise and fall of the car-body on its springs be transmitten to or in any manner adversely affect any portion of the

driving mechanism. In the event of an excessive rise of one side of the car-body on its springs and a simultaneous lift of the ends of the counter-shaft and axle at the opposite side of the car the counter-shaft and armature-shaft would be slightly out of their normal lines and inclined in opposite directions; but, nevertheless, the hinge connections between the axle and the frame-arms and the ball-bearings of the counter-shaft and the ball wrist-pins on the counter-shaft crank-disks will obviate all binding effects between the motor and the gear on the axle. 75

The speed of an electric motor is usually too great to warrant its direct application to the axle B, and hence reducing-gearing of some kind has usually been employed, and such gearing may be widely varied in its 85 character without departure from that portion of my invention which includes the counter-shaft, however it may be geared to the axle, provided it is supported on said axle, is hinged thereto and to the motor, and 90 is coupled to the latter by one or two pitmen. I have, however, devised special gearing for connecting the counter-shaft D with the axle B. At about the middle of the axle there is a large split gear E, the parts of which are 95 united by bolts in a manner well-known, and this gear meshes at its upper side with a pinion F, loosely mounted on the counter-shaft. This gear F has hub-like extensions 100 i, on which are keyed two flanged disks k k', 100 having oppositely-inclined or outwardly-beveled peripheries. Coincident with the outer sides of the disks k and k' there are two flanged disks l l', each of which has an annular interior inclined surface which corresponds with the inclined surface of the periphery of the adjacent disk, and one or the other of these two surfaces is preferably clad with leather to afford desirable frictional contact. The disks l l' are splined to the counter-shaft, but are free to be moved longitudinally thereon, and they have hubs at their outer sides which are externally threaded. Each of these disks l l' is backed up by a 110 heavy rubber spring m m', abutting against a sleeve n n', which is firmly pinned to the counter-shaft. Interposed between each spring and the adjacent disk l or l' there is a disk o, having an annular projection or sleeve which surrounds a portion of the screw-threaded hub of the disk and abuts at its end or edge against the side of an annular nut p, which is tapped to the thread of the hub. The nuts p are provided with radial holes or 115 with projecting spurs, so that by use of a 120 spanner-wrench they may be rotated for adjusting the springs and varying the degree of frictional contact at the disks. These pairs of disks l m and l' m' correspond in structure to the well-known contact-faces commonly 125 employed in friction-clutches; but in my organization no true clutching action is involved, inasmuch as said disks serve solely 130 as yielding gearing connections between the

positively-driven counter-shaft and the axle B, and said disks are not thrown in and out of contact, as in the case of a friction-clutch. By compressing the two springs *m m'* the frictional contact of the disks may be so graduated that if the motor or the gearing should be subjected to undue driving strains the disks will slip and thus obviate liability of injury to any portion of the mechanism in the event 10 of reckless overloading or in the case of sudden stoppage of the locomotive, as in abrupt braking, or in collisions.

I am aware that friction-clutches have been heretofore employed in connection with the 15 gearing of an electric locomotive, and also that friction-pulleys have been heretofore used; but I am not aware that frictional contacts have heretofore been employed as a safety medium between a counter-shaft which 20 is positively coupled to and driven by the electric-motor shaft and connected by toothed gearing with an axle.

Should belts be employed for connecting the motor-shaft with the counter-shaft, the 25 friction-disks would have little or no value, because the belts would ordinarily slip under undue strains; but in that case, although belts are deemed objectionable, the counter-shaft in bearings in a frame hinged to the 30 motor and carried on the axle would be of value, although the pinion might then be keyed to the counter-shaft. When the counter-shaft is driven positively from the motor-shaft, or, in other words, when these shafts 35 are connected by any means which will admit of no slipping action, the friction-disks will always prove of special value, and the driving-connection of the counter-shaft and axle by means of toothed gearing, as by the pinion 40 and gear, is a far more reliable and effective connection than friction-pulleys can afford.

With a comparatively low-speed motor and small driving-wheels the speed of the axle may be properly reduced by the use of the 45 one pinion and gear here shown—as, for instance, I have obtained good results with one revolution of the axle to four revolutions by the motor-shaft and counter-shaft.

With specially high speed at the motor idle- 50 gears may obviously be loosely mounted on the counter-shaft and axle for reducing the speed of the latter to any desired extent, in which case the loose gear on the counter-shaft would preferably be located near one of its 55 friction-disks, and have a long hub at one side on which one or more of the idle-gears would be loosely journaled, the other idle-gears being in like manner journaled on the driving-axle.

60 The pinion F and the gear E are inclosed within a casing G, constructed in two parts bolted together, and so embracing the hubs of the gear F and the axle B as to be firmly supported thereon. This casing excludes 65 dust and dirt from the gearing and is tight enough to carry an abundant charge of lubricating-matter, and also serves to deaden

such sounds as are usually incident to rapidly-driven gearing. As the lower end of this casing is located but little above the level of 70 the rails, I protect it against striking possible obstructions by front and rear pendent guards H.

As results of my invention I am enabled to produce electric locomotives which are especially efficient, reliable, and durable, and their simplicity and lightness involve substantial economy in construction and maintenance, and in addition thereto watches can be safely carried thereon.

Having thus described my invention, I claim as new, and desire to secure by Letters Patent—

1. In an electric locomotive, the combination, with a car-body, driving-axle, and suitable gearing, of an electric motor provided with an armature and a shell or casing which constitutes a part of the magnetic system of the motor and in part serves as an effective magnetic shield between the interior of the 85 car or locomotive and the magnetic field developed by the field-coils of the motor, substantially as described, whereby watches carried by persons riding on said locomotive are protected against injury by exposure to magnetization.

2. In an electric locomotive adapted to use as a passenger-car, the combination, with the driving-axle and suitable gearing, of an electric motor having a magnetic shell or casing 100 which incloses the field-coils and armature, is attached to the under side of the sill-framing of the car, and constitutes a part of the magnetic system of the motor, and in part serves as an effective magnetic shield or guard for 105 preventing the projection of magnetism upward into the car, substantially as described.

3. In an electric locomotive, the combination, with the driving-wheels, their axle, and suitable driving connections, of an electric 110 motor having an armature provided with an iron core, field-coils which surround the armature, and a magnetic shell or casing which surrounds the armature and field-coils and is attached to and carried by a spring-mounted 115 portion of the locomotive.

4. In an electric locomotive, the combination, substantially as hereinbefore described, of a spring-supported car-body, an electric motor carried by and suspended from said car-body, a driving-axle, a counter-shaft which is free to rise, fall, and tilt with said axle, gearing connecting said axle and counter-shaft, and crank-disks and links connecting the motor-shaft with said counter-shaft.

5. In an electric locomotive, the combination, substantially as hereinbefore described, of the driving-axle, a counter-shaft carried on said axle above and parallel therewith, a gear and pinion for coupling said shaft and axle, 130 an electric motor, frame-arms, which are hinged at one end to the motor and have at their opposite ends bearings for said counter-shaft, crank-disks on the motor-shaft and

counter-shaft, and a pitman connecting said crank-disks.

6. In an electric locomotive, the combination, substantially as hereinbefore described, 5 of the driving-axle, a counter-shaft above and carried upon said axle, an electric motor, frame-arms hinged to the motor and affording bearings for the counter-shaft, pitmen and cranks connecting both ends of the motor-shaft with both ends of the counter-shaft, and a gear and pinion connecting said counter-shaft and axle.

7. In an electric locomotive, the combination, substantially as hereinbefore described, 15 of a driving-axle, a counter-shaft carried by said axle parallel therewith and normally in the same vertical plane, an electric motor having an armature-shaft which is normally parallel with said counter-shaft and axle and 20 normally in the horizontal plane occupied by the counter-shaft, means for communicating power, respectively, from the motor to the counter-shaft and from the latter to the axle, and hinged arms which maintain the counter-shaft and armature-shaft at a uniform 25 distance from each other.

8. In an electric locomotive, the combination, substantially as hereinbefore described, of a driving-axle, a counter-shaft carried 30 upon, parallel with, and normally in the same vertical plane as said axle, a motor having an armature-shaft normally parallel with said counter-shaft and axle and normally in the same horizontal plane as the counter-shaft, 35 hinged arms which maintain the armature-shaft and counter-shaft in uniform relations, pitmen and cranks connecting the ends of the armature-shaft to the ends of the counter-shaft, and a gear and pinion operatively 40 connecting the counter-shaft and axle.

9. In an electric locomotive, the combination, substantially as hereinbefore described, of a driving-axle, a counter-shaft which is

above and carried by said axle and is coupled thereto by means of a gear on the axle and a 45 frictionally-driven pinion on the counter-shaft, and an electric motor by which said counter-shaft is positively driven.

10. In an electric locomotive, the combination, with an electric motor, of a counter-shaft 50 positively driven by the motor and geared to a driving-axle by a pinion on said counter-shaft, which is rotatively connected therewith by means of friction-disks backed by adjustable springs, substantially as described. 55

11. In an electric locomotive, the combination, substantially as hereinbefore described, of an axle, and a counter-shaft which is carried above and upon the axle, is driven by an electric motor, has bearings in frame-arms which 60 are hinged to the motor, and is coupled to said axle by toothed gearing.

12. In an electric locomotive, the combination, substantially as hereinbefore described, of a driving-axle, a counter-shaft parallel with 65 and carried by said axle, a pinion on said shaft meshing with a gear on the axle, and a housing suspended on said shaft and axle and completely inclosing the gearing for serving as a protector thereto and also as a reservoir 70 for lubricating matter in which the gearing may revolve.

13. In an electric locomotive, the combination of an axle, a counter-shaft carried above and upon the axle and geared thereto, an electric motor, a crank and pitman for positively coupling the armature-shaft to a crank having a ball wrist-pin on the counter-shaft, and frame-arms hinged to the motor and having ball-bearings for said counter-shaft, substantially as described. 75 80
